UNITED STATES PATENT OFFICE.

ALBERT SEATON AND WILLIAM O. RADER, OF INDIANAPOLIS, INDIANA, ASSIGNEES
TO ELI LILLY AND COMPANY, OF INDIANAPOLIS, INDIANA, A CORPORATION OF
INDIANA.

PRODUCT AND METHOD FOR TESTING SUGAR TOLERANCE.

No Drawing.

Application filed June 4, 1926. Serial No. 113,811.

In making physical examinations of individuals for various purposes, especially in connection with examinations for life insurance, a most desirable test and one that is rapidly growing in use is the sugar-tolerance test. By thus determining the tolerance which the subject has for sugar, any tendency toward diabetes mellitus will be disclosed.

- 10 The test consists in having the patient take a specified quantity of sugar, desirably glucose, usually in water solution, and making an examination of a specimen of his urine taken a definite time after the ingestion of the sugar, to determine how much if any of the sugar passed through into the urine. Such a test is not new with us, but has been recognized as desirable for some time.
- 20 However, certain psychological difficulties frequently arise in connection with the making of such a test. The specimen of urine may not be obtained within a suitable time after the ingestion of sugar, whether by accident or intent. For various reasons the person being examined may not retain the sugar administered to him; or he may not take the sugar at all, although he was instructed to do so and may say that he did it.
- 30 Because of the various personal equations thus involved, and of the fact that the taking of the sugar and the obtaining of the specimen of urine are necessarily some distance apart in time and necessarily largely or wholly under the control of the person being examined, and because the specimen obtained must frequently be shipped to a distant point for examination (as to the home office of an insurance company), the sugar-tolerance test as heretofore made has not been reliable. An insurance company, for instance, has not been able to tell that an applicant for insurance actually took the required sugar, or that he retained it, or that the specimen of urine was obtained at the proper time after the sugar was taken. In consequence, the truth was hard to find.

It is the object of our invention to make the truth of the situation easier to find. To that end, it is our object to provide a positive indication of these various things which were always doubtful heretofore, such as whether or not the sugar was taken and retained, and whether or not the specimen of

urine was obtained at the proper time; and to provide this indication in the specimen itself, so that the chemist at the home office of the insurance company can positively determine the facts of this situation.

To that end, more specifically stated, it is the object of our invention to provide a sugar (desirably glucose) containing a substance which will have the following characteristics:

1. Solubility at least as great as that of the sugar used.
2. Non-discoverability by the subject, whether by color, taste, or smell.
3. Freedom from chemical reaction with the sugar used, whether rapidly or slowly.
4. Physiological inertness.
5. Certainty of passing through into the urine within a certain time after being taken.
6. Freedom from chemical reaction, whether rapid or slow, with the urine itself or the usual preservatives used therefor.
7. Freedom from any chemical reaction that would interfere with any quantitative or qualitative urinary test, as for albumin or sugar.
8. Sufficient cheapness so that it can be placed in all specimens of sugar to be administered, whether it is to be tested for or not.
9. Responsiveness to a practical and simple test for its presence in the urine.

We have found that we can obtain these results by providing a suitable indicator in the sugar which is administered to the subject. One such suitable indicator substance is soluble saccharin, or sodium benzosulphide.

A very small proportion of this saccharin mixed with the glucose to be administered is found to fulfill all the necessary requirements. We find that one part of saccharin in from 1000 to 2000 parts of glucose gives excellent results, although no precise proportions are essential to our invention. A convenient proportion is one grain of saccharin per 100 grams of glucose; and as 100 grams of glucose in 8 ounces of water is the usual quantity administered for the sugar-tolerance test, that means the administration of 1 grain of saccharin in making the test.

In addition, we may add some flavoring

extract to the glucose, such as wintergreen, to make the taking of the glucose less distasteful—as it is found that the taking of 100 grams of unflavored glucose in 8 ounces of water is distasteful to many people. The presence or absence of the flavor is merely incidental, however, and has nothing to do with our invention.

Upon administration of this saccharin-containing glucose, a sufficient time is allowed, and the urine specimen is obtained. If the time is proper, usually from two to three hours after ingestion, the saccharin will appear in the urine; but if the time is not proper, the saccharin will not appear. Sugar in various forms and quantities may appear in the urine, according to the tolerance of the individual for the sugar.

The presence of the saccharin in the glucose does not affect the physiological action of the glucose, or any other physiological function which is involved in urinary tests. The saccharin cannot be detected in the glucose by color, taste, or smell, and does not react at all with the glucose.

When the specimen of urine is obtained, any usual preservative is added, and the specimen sent to the home office of the interested insurance company. The saccharin does not react on any usual preservative, and does not interfere with any of the usual urinary tests.

The presence of the saccharin in the urine may be determined by a known and relatively simple test, which does not greatly interfere with the other work of the analyst, and does not require extended close watching. The reaction is distinct, and there is small chance of error. The test which we prefer to use for the presence of the saccharin in the urine is as follows:

A small quantity of the urine to be tested is acidified slightly with phosphoric acid; and is then evaporated down to a thick paste, with care that none of the paste is lost toward the last by excessive heating. This paste is extracted with several small portions of ether, and the ether extracts are filtered off, and the several ether extracts are combined and evaporated to thickness over a water bath. The residue is transferred to a test tube, a pinch of dry resorcin is added, and then a few drops of concentrated sulphuric acid are added. This is heated until the mass begins to swell, and is then cooled until action ceases. This heating and cooling is desirably repeated several times. After the final cooling, the material is diluted with water, and neutralized with

sodium hydroxide. At the neutral point, a red-green fluorescence gives a positive indication of the presence of saccharin; while the absence of such fluorescence indicates that saccharin was not present, and thus indicates that the subject (usually an applicant for insurance) did not take or retain the sugar furnished him, or that the specimen of urine was not obtained at the required time after the ingestion of the sugar.

We claim as our invention:—

1. The process of testing an individual for sugar tolerance, which consists in administering a quantity of sugar mixed with a small amount of an indicator which will appear in the urine within a definite time after ingestion but which is not apparent to the individual being tested, obtaining the urinary specimen, and testing it for the presence of sugar and for the presence of such indicator.

2. The process of testing an individual for sugar tolerance as set forth in claim 1, with the addition that the indicator is saccharin.

3. A substance for use in making sugar-tolerance tests on individuals, comprising a mixture of sugar with an indicator which will appear in the urine within a definite time after ingestion of the mixture, but which is not apparent to the individual being tested.

4. A substance for use in making sugar-tolerance tests on individuals, comprising a mixture of sugar with an indicator which will appear in the urine within a definite time after ingestion of the mixture and which does not interfere with the usual urinary tests, but which is not apparent to the individual being tested.

5. A substance for use in making sugar-tolerance tests on individuals, comprising a mixture of sugar with an indicator which will appear in the urine within a definite time after ingestion of the mixture and which does not interfere with the urinary test for sugar, but which is not apparent to the individual being tested.

6. A substance for use in making sugar-tolerance tests in individuals, comprising a mixture of sugar with a relatively small amount of saccharin.

In witness whereof, we have hereunto set our hands at Indianapolis, Indiana, this 3rd day of June, A. D. one thousand nine hundred and twenty-six.

ALBERT SEATON.
WILLIAM O. RADER.
